EJECTING DEVICE FOR THE FOLDING MANDRELS OF PAPER BAG MAKING MACHINES

Filed Aug. 9, 1929

FIG. 2

FIG. 4

FIG. 5

Paul Gangler
INVENTOR;
By *Atchenuk*
his Attorney.

UNITED STATES PATENT OFFICE

PAUL GANGLER, OF ESSLINGEN, GERMANY, ASSIGNOR TO THE FIRM FR. HESSER,
MASCHINENFABRIK-AKTIENGESELLSCHAFT, OF STUTTGART-CANNSTATT, GERMANY

EJECTING DEVICE FOR THE FOLDING MANDRELS OF PAPER BAG-MAKING MACHINES

Application filed August 9, 1929, Serial No. 384,536, and in Germany August 29, 1928.

My invention relates to improvements in machines for the manufacture of bags from paper, cardboard or other suitable materials, and more particularly to machines of that type in which the bag is made on folding mandrels, which are in succession presented to the devices serving for the formation of the bag on the folding mandrels.

My invention consists of an improved device for removing the finished bag from its mandrel. Hitherto an ejecting plate was generally used for this purpose, which had substantially the size of the entire front face of the folding mandrel. This plate fits into a countersunk portion recessed in the front face of the mandrel, said recess corresponding with the size of the said ejecting plate and serving simultaneously as a stop or abutment for limiting the inward movement of the plate which is joined to a rod guided in the interior of the mandrel. By means of this rod, the ejecting plate is during the ejecting process advanced by the distance necessary for stripping the finished bag off the mandrel and is then again drawn back into the countersunk portion at the front end of the mandrel.

An essential drawback of the known ejecting devices of this type is that during the return movement of the ejecting plate the paper bag is liable to be pulled back again by a certain amount and to be clamped between the ejecting plate and the said countersunk portion at the front end of the mandrel, whereby the operation is disturbed and breakdowns may be caused in the machine.

The object of my invention is to simplify the construction of the ejecting device and to eliminate the said drawback. In order to realize this object, the ejecting plate and the countersunk portion at the front end of the mandrel have been eliminated by providing a rod or tube of as large a cross-sectional area as possible for ejecting or stripping the bag from or off the mandrel, such rod being

adapted to be moved axially within the mandrel in a similar manner to the rod of the ejector plate used heretofore, but extending with its front end up to the front face of the mandrel and terminating flush with it, so that the front end of the rod forms part of the front face of the mandrel and directly serves for stripping the bag off the folding mandrel. Instead of one rod, two or more rods presenting together as large a cross-section as possible may be used.

Some embodiments of my invention are illustrated by way of example in the accompanying drawing, in which

Fig. 1, shows a longitudinal section through one embodiment,

Fig. 2, a cross-section along line *a*—*b* of Fig. 1,

Fig. 3, a modification,

Fig. 4, a cross-section along line *c*—*d* of Fig. 3,

Fig. 5, a further modification, and

Fig. 6, a cross-section along line *e*—*f* of Fig. 5.

Like parts are indicated by like reference characters throughout all the figures of the drawing.

In the present case a part of a paper bag making machine has been illustrated in which the folding mandrels 1, one of which is only shown in each longitudinal section in the drawing, are secured in the well known and usual manner on a disc 2 in the fashion of the spokes of a wheel. As is also well known to those skilled in the art, said disc 2 is intermittently rotated by means of a suitable known drive operating a shaft 3 journaled in a suitable bearing 4 of the machine framing so that the folding mandrels reach in succession suitable and well known devices by means of which the blank, for instance a sheet of paper, is first folded around the mandrel to form a tube and the longitudinal edges of said tube are cemented together to form the longitudinal seam of the bag, and

then the bottom of the bag is produced on the front face of the mandrel.

For ejecting the thus finished bag P, I provide in the embodiment illustrated in Figs. 1 and 2 a tube 5 which preferably has as large a diameter as possible and is axially slideable in the hollow mandrel 1, for instance within suitably shaped inward extensions 8. The tube 5 is with its inner end mounted upon the horizontal branch or projection 6^a of a block 6 adapted to be moved axially in a longitudinal slot 7 of the mandrel. For sliding the block 6 with the tube longitudinally within the mandrel an extension 6^b is provided which during the rotation of the mandrel wheel is guided in a suitable annular groove 9 of the bearing 4 at all working stations with the exception of the ejecting station. Only at this ejecting station, the fork-shaped end 11^a of a rod 11 extends in the well known manner into a corresponding recess of the guide track 4^a. Said rod 11 is operated by well known driving and controlling means so as to effect the necessary outward and inward motions of the block 6 and thus of the ejector tube 5. At its front end, the ejector tube is closed by a lid-like disc 12 which lies flush with the front face 1^a of the folding mandrel 1, so that the lid 12 forms a uniform abutment surface with the remaining front face 1^a of the mandrel.

During the rotation of the mandrel spider, the rod 11 with the fork 11^a is located in its inner position shown in Fig. 1 in full lines. At the ejection station, the projection 6^b of the block 6 passes from the guide groove 9 into the fork 11^a, and the outward motion of the tube 5 takes place into the position shown in broken lines on the right-hand side of Fig. 1, by means of the rod 11 and the block 6. The bag P is thereby stripped off the mandrel 1 and placed on the tray or other support 19. The ejector tube 1 is then pulled back by the rod 11 into its inner position. The inward stroke of the ejector tube 5 is limited by a projection 6^c of the block 6 which encounters the bottom wall of the hollow mandrel 1. It will be understood that the tube might be replaced by a full rod and that the tube or rod might also have another cross-section than a circular one.

In the modification illustrated in Figs. 3 and 4, two flat bars or rails 14^a and 14^b are employed instead of the tube 5. Said bars or rails are at their inner ends secured to the said block 6 which is operated in the same manner as described with reference to Fig. 1. The rails are guided at the top in longitudinal grooves 16 of suitable projections 17 and at the bottom in angular recesses 20 of suitable projections 21 of the hollow mandrel 1. At the front end, the flat rails 14^a and 14^b extend to the front face of the folding mandrel and lie flush with it. The mode of operation is the same as described with ref-

erence to the construction shown in Figs. 1 and 2.

In the modification of my invention illustrated in the Figs. 5 and 6, two rods 18^a and 18^b one above the other are provided for ejecting or stripping the bag off the mandrel. At their inner ends, the two rods are secured to the block 6, while the front ends of the two rods lie flush with the front face of the mandrel 1. In this case, the extension 18^c of the rod 18^b serves as a stop for limiting the inward motion of both ejector rods. The mode of operation of this modification is also equal to that described with reference to the construction illustrated in Fig. 1.

It will be understood that according to the size and the cross-section of the folding mandrel it is also possible to employ more than two rails or rods in suitable relative arrangement, and that various other changes may be made without departing from the spirit of my invention.

I claim as my invention:—

1. In an ejecting device of the type specified for the folding mandrels of paper bag making machines, rod shaped ejecting means extending with the operative end up to and flush with the front face of the folding mandrel and adapted to be axially reciprocated within said mandrel.

2. In an ejector device of the type specified for the folding mandrels of paper bag making machines, rod shaped ejecting means extending with the operative end up to and flush with the front face of the folding mandrel and guided in said mandrel for axial movement, and means adapted to hold said rod shaped means and to be reciprocated axially within said mandrel, said holding means consisting of a block-like piece guided for axial reciprocation in a longitudinal slot in the wall of the hollow mandrel and having a projection adapted to be engaged by the reciprocating driving means and another projection adapted to abut in the inner position of the rod-shaped ejecting means against a stop of the mandrel.

3. In an ejecting device of the type specified for the folding mandrels of paper bag making machines, a smooth ejecting rod of relatively large diameter extending with its front operative end up to and flush with the front face of the folding mandrel and adapted to be axially reciprocated within said mandrel.

4. In an ejecting device of the type specified for the folding mandrels of paper bag making machines, rod shaped ejecting means extending with the operative end up to and flush with the front face of the folding mandrel and adapted to be axially reciprocated within said mandrel, said rod shaped means consisting of a hollow tube having a closing lid at its front end.

5. In an ejecting device of the type specified for paper bag making machines having hollow folding mandrels, rod shaped ejecting means extending with the operative end up to and flush with the front face of the folding mandrel and adapted to be axially reciprocated within said mandrel, said rod shaped means consisting of a hollow tube of relatively large diameter and guided for axial reciprocation between inner projections of the mandrel wall.

In testimony whereof I have affixed my signature.

PAUL GANGLER.
